MANOEUVERING OR OPERATING DEVICES**Gustav (Gösta) Adolf Forsberg, Sandviken, Sweden**
Application September 13, 1955, Serial No. 534,088**5 Claims. (Cl. 121—46)**

The present invention relates to an operating or manoeuvring device which is specially suitable for loading and shovelling machines comprising a piston reciprocating in a cylinder.

Such operating devices have previously been used in such machines. Such loading machines are normally mounted on a tractor and comprise an arm, swingably connected to the tractor and carrying a shovel supported by a double armed lever which is pivotally mounted on the arm. A hydraulically operating device, as a cylinder with a reciprocating piston, is provided for turning the shovel carrying lever and a second hydraulically operated device is provided on the tractor for raising and lowering, respectively, the arm.

The conventional machines are designed in such manner that the piston side connected with the piston rod and having a smaller operative surface than the opposite side of the piston performs the heavy shovel lifting work.

It is, therefore, one object of the present invention to provide an operating device which lacks the inherent drawbacks of the known devices.

It is another object of the present invention to provide an operating device for changing the distance between two bearing members spaced apart from each other which device comprises a cylinder and a piston reciprocating therein, the cylinder and piston being arranged in such manner that pressure exerted upon the free side of the piston reduces the distance between the bearing members while pressure upon the piston rod carrying side of the piston increases such distance.

It is still a further object of the present invention to provide an operating device for a loading machine including a shovel, which device comprises a cylinder and a piston reciprocating therein, and a lever pivotally mounted on a lifting arm, said piston being connected with one end of the lever in such manner that the shovel is disposed opposite the free side of the piston, while the bearing member rigidly secured to the loading machine is disposed on the piston rod carrying side of the piston.

With these and other objects in view which will become apparent in the following detailed description, the present invention will be clearly understood in connection with the accompanying drawings, in which:

Figure 1 is a side elevation of a tractor with a loading device of conventional structure;

Fig. 2 is a side elevation, partly in section, of the operating means for a loading device of Fig. 1;

Fig. 3 is a side elevation, partly in section, of the operating device according to the present invention;

Fig. 4 is a plan view, partly in section, the device shown in Fig. 3;

Fig. 5 is a section along the lines 5—5 of Fig. 3; and Fig. 6 is a section along the lines 6—6 of Fig. 3.

Referring now to the drawings, and particularly to Figs. 1 and 2, an operating device as used in conventional loading machines is disclosed. The loading machine is normally mounted on a tractor and comprises an arm 1 swing-

ably connected to the tractor and carrying a shovel 2 supported by a double armed lever 3 which is pivotally mounted on the arm 1. Two hydraulically operated devices 5 and 6, serve the purpose of lifting and lowering, respectively, the arm 1 and the shovel 2, respectively.

As may be readily seen, in order to lift the arm 1 a pressure fluid is supplied through the tube 7 to one end of the cylinder of the device 5, whereas pressure fluid is ejected through the tube 8 at the other end of the cylinder. When the arm 1 is lowered the process is reversed, i. e., pressure fluid enters through the tube 8 and fluid is ejected through the tube 7. When the arm 1 is lifted, pressure is exerted upon that side of the piston of the device 5 which is opposite the piston rod and which has a larger effective area than the other piston side, the effective arm of which is much smaller. When the arm 1 is to be lifted, the pressure fluid exerts its maximum force upon the piston, an arrangement which is desirable and bringing about the best effect. If it is assumed that the pump delivering the pressure fluid works at a predetermined rate, it is also possible to provide an arrangement in which the lifting of the arm 1, which is obviously, by far, a heavier operation than its lowering, is performed by great force and a certain moderate speed, while the lowering of the arm is performed by a moderate force but relatively high speed, because when the arm 1 is lowered the space occupied by the piston rod does not need to be filled with pressure fluid.

In respect to the operating device 6, the situation is not 30 advantageous as shown in connection with the device 5, but rather of disadvantage. When the shovel 2 supported by the double armed lever 3 is to be lifted, which obviously here also is the heaviest operation, pressure is exerted upon the less effective side of the piston of the device 6, i. e. the side where the piston rod is connected, by pressure fluid supplied through a tube 9. The lifting is therefore performed only by a moderate force. When the shovel 2 is to be lowered or emptied, i. e. swung clockwise in Fig. 1, this is performed by supplying the fluid through the tube 10 and removing fluid through the tube 9, in other words, pressure is exerted upon the "free" area of the piston, whereby the operation is performed by great force.

These drawbacks could naturally be obviated by arranging the operating device 6 under or below the arm 1, i. e., being in engagement with the shaft 3 or the shovel 2 on the other side of the fulcrum point 4. Such an arrangement would, however, involve still greater disadvantages due to the lack of space and other obvious drawbacks, and it can, therefore, not be adapted. In order to reduce, at least a little, the disadvantageous influence of the "position" of the piston rod of the operating device 6, the diameter of the part 11 of the piston rod which is directly cooperating with the cylinder is usually reduced as indicated in Fig. 2, but this measure while improving slightly the operation, is not a satisfactory solution to the present problem.

Referring now to Figs. 3 to 6 of the drawing where an operating device in accordance with the present invention is disclosed, sleeve-formed bearing members 12 and 13 or the like for mounting the operating device in engagement with elements to be lifted, e. g., the lever 3 of the shovel 2 and the arm 1 of the loading machine (Fig. 1), are provided, the distance between the bearing members 12 and 13 being increased and decreased, respectively, by means of the operating device. Two plate formed parts 14 and 15 are fastened to the bearing member 12 and to these parts is in turn fastened, suitably by welding or soldering or brazing, one cylinder head or cover 17 of the cylinder 16 of the device. The cylinder head 17 and a second cylinder head 18, disposed at the other end of the cylinder

16, are advantageously interconnected by tension rods or drag bars 19 or the like (Figs. 5 and 6). In the embodiment shown in the drawing, the cylinder heads 17 and 18 have a square form, the tension rods 19 being arranged preferably at the corners of the cylinder heads. In the cylinder, there is in the conventional manner (by influence of pressure fluid) reciprocating a piston 20 with a piston rod 21 projecting through and sealing against the cylinder head 17 disposed nearest to the member 12. The piston rod 21 has fastened thereto a cross-head 22 which together with the piston rod 21 forms a T. On the end faces 23 and 24 of the cross-head 22 are mounted one of the ends of two rods or links 25 and 26, respectively, the other of the ends of which are rigidly fastened to the bearing member 13. In order to increase the rigidity of the rods 25, 26, two stiffening plates or struts 27 and 28 are arranged between them.

As will be apparent from the above description the bearing member 13 connected to the piston rod 21 is disposed on that side of the cylinder 16 which is opposite the piston rod 21, while the bearing member 12 connected to the cylinder 16 is situated on the same side of the cylinder as is the piston rod 21. This arrangement which can be said to be reversed, as compared with the conventional arrangement, shown in Fig. 2, offers very remarkable advantages. By supplying pressure fluid through a tube connection 29 to the cylinder 16 to the right of the piston 21 in Figs. 3 and 4, a reduction of the distance between the members 12 and 13 and, thereby, of parts connected thereto, is obtained. At the operation for reducing the distance between the bearing members, the effective free area of the piston is in operation and not reduced by the piston rod as is the case in the known device shown in Fig. 2. When using the manoeuvring or operating device according to the present invention, shown in Figs. 3-6, instead of the device 6 shown in Fig. 1 and disposed above the arm 1, the full or maximum force and the greatest torque or turning moment are obtained at the heavy operation, i. e., when the shovel 2 is lifted or swung counter-clockwise in Fig. 1. That the operation at a certain predetermined pump speed is performed at a relatively moderate speed is likewise an advantage. At the light operation, i. e. when the shovel is lowered or swung clockwise in Fig. 1, a faster movement of the shovel is obtained at an unchangeable pump speed. The emptying of the contents of the shovel 2 as well as of the pressure fluid in the cylinder 16, at the right of piston 20 in Figs. 3 and 4, are thus performed rapidly which is desirable because of the saving of time.

A further great advantage of the present invention resides in the fact that the cylinder head 18 is readily removable, e. g. when the piston 20 or packings of the piston 20 shall be replaced or when other maintenance work or inspections must be performed. The corresponding cylinder head of the hitherto used devices is not removable but fastened to one of the bearing members, as may be seen in Fig. 2, in which the head 31 is secured to the bearing member 32. An exchange of the packings has, therefore, hitherto been considerable work. It is obvious that the present invention is not limited to the embodiments described above and shown in the accompanying drawings, since other embodiments are possible within the scope of the invention. Thus other connecting elements or devices between the bearing member

12 and the cylinder 16 or the bearing member 17 and the piston rod 21 may be used instead of the plates 14 and the rods 25 and 26, respectively. Further one or both of the cylinder heads 17 and 18 may be mounted in deliberate or arbitrary manners other than shown.

10 The piston rod 21, which for obvious reasons is rather sensitive, is well protected against blows or shocks, by the parts 14, 15, 22, 25 and 26, which are surrounding the same. These parts may, if desired, readily be so dimensioned that they completely enclose the piston rod 21, which thus is protected also against dirt, dust and the like. Such variation is indicated in Fig. 5 by dotted lines and may be such that the parts have a relatively small mutual play, e. g., 0.1-0.5 mm., which may be filled up with sealing lubricants. The rods 25 and 26 which may be of U-profile and the width and thickness, respectively, of the cross-head 22 are then substantially the same as the distance between the plates 14 and 15.

15 While I have disclosed several embodiments of the present invention, it is to be understood that these embodiments are given by example only and not in a limiting sense, the scope of the present invention being determined by the objects and the claims.

I claim:

20 1. A device for changing the distance between two bearing members comprising a cylinder, first means for pivotally connecting said cylinder in one of said bearing members, and a piston reciprocating in said cylinder and secured to a piston rod, second means for connecting said piston rod with the other of said bearing members, said first connecting means comprising a pair of plates disposed in substantially parallel planes spaced apart from each other, one end of each of said plates being secured to said one of said bearing members and the other end 25 of each of said plates being secured to said cylinder; and said second connecting means comprising a pair of rods spaced apart from each other and a cross-head connecting opposite ends of said rods and secured to the free end of said piston rod, said cross-head reciprocating together with said piston rod between said plates axially, and said one of said bearing members being stationary while the other of said bearing member changes its distance from said one of said bearing members responsive to the position of said piston in said cylinder.

25 2. The device, as set forth in claim 1, in which said cross-head moves along a path between said one of said bearing members and the head of said cylinder remote from said other of said bearing members.

30 3. The device, as set forth in claim 1, in which said plates are rigidly connected to said cylinder.

35 4. The device, as set forth in claim 1, in which said plates and said rods are of respective cross sections to form guides relative to each other.

40 5. The device, as set forth in claim 1, in which said plates and said rods complement each other to form a cover for said piston rod during the reciprocating movement of the latter.
